UNITED STATES PATENT OFFICE

CLAUDE C. CROUCH, OF HILSDALE, WISCONSIN, ASSIGNOR OF ONE-FOURTH TO
FRANCIS E. SPRAGUE, OF HILSDALE, WISCONSIN, AND ONE-FOURTH TO ALEX K.
McDONALD, OF BARRON, WISCONSIN

SANITARY BRUSH

Application filed November 15, 1929. Serial No. 407,536.

This invention relates to a sanitary brush.

The object of my invention is the construction of a simple and efficient brush to be used especially by barbers in the treating of 5 the hair of human beings, or for scalp treatment, as each case or customer desires.

Another object of my invention is the construction of a very efficient brush which is of a fountain type, and which can be easily 10 manipulated by the operator for most advantageous results.

A still further object of my invention is the construction of a simple and efficient brush, the parts of which can be quickly separated or disassembled for cleaning the 15 brush; when the parts are cleaned, they can likewise be quickly assembled, whereupon the brush will be ready for use.

With the foregoing and other objects in 20 view, my invention comprises certain novel constructions, combinations and arrangements of parts as will be hereinafter fully described, illustrated in the accompanying drawings, and more particularly pointed out 25 in the appended claims.

In the drawings:

Figure 1 is a top plan view of a brush constructed in accordance with the present invention, while

30 Figure 2 is a vertical, longitudinal sectional view of the same.

Figure 3 is an enlarged, fragmentary bottom plan view of the brush.

35 Figure 4 is a transverse sectional view taken on line 4-4, Figure 2, and looking in the direction of the arrows.

Figure 5 is an enlarged perspective view of the control device.

40 Figure 6 is a top plan view of the frame of the brush head.

Figure 7 is a view partly in plan and partly in section of another embodiment of my brush.

45 Figure 8 is a top plan view of the screen shown in Figure 7, while

Figure 9 is a top plan view of the cover of the casing shown in Figure 7.

50 Figure 10 is a transverse sectional view taken on line 10-10, Figure 7, and looking in the direction of the arrows.

Figure 11 is a fragmentary plan view of a rubber toothed frame, while

55 Figure 12 is a transverse sectional view taken on line 12-12, Figure 11 and looking in the direction of the arrows.

Figure 13 is an enlarged sectional view taken on line 13-13, Figure 1 and looking in the direction of the arrows.

Referring to the drawings by numerals, 1 designates the body casing and 2 is the hollow, 60 integral handle thereof. The handle 2 is of suitable shape to be easily grasped by the operator and said handle constitutes a reservoir for the liquid to be used in the brush. The handle is filled at 3 when the stopper or 65 cap 4 is removed. At the inner end of the handle is a rigid closure tit 5 upon which is placed one end of the apertured rubber tube 6 (Fig. 2). The tube 6 is suitably perforated to allow well-spreading of the liquid, as indicated in Figure 4.

70 The outwardly-bulging body casing 1 is provided interiorly on its sides with grooves 7 and 8; the grooves 7 are in horizontal alignment, and the grooves 8 are likewise. A 75 screen frame 9, with the mesh center, is slid into grooves 8, from the outer end of the brush casing 1 (Fig. 2) and the frame 10 of the brush head 11 is slid into the grooves 7 from the outer end of casing 1 towards its inner end. The frame 10 of the brush head is provided with a rearwardly extending 80 protecting tongue 12, which guards the rubber tube 6 near the tit 5. The rubber tube 6 is adapted to lie on screen 9 and the liquid sprayed from this tube falls through the 85 screen onto the brush head.

85 The brush head 11 comprises said frame 10 with its longitudinally extending bristle-holding bars 13 and reinforcing V-shape bar 90 14, transverse bar 15 and X-bar 16; these reinforcing bars make a very durable and efficient brush head. The bristles 17 are very strong, in fact, the first test may be as severe as stepping upon the bristles without doing 95 any injury.

To prevent accidental movement or displacement of the brush head, I form, on the side edges of the frame 10, locking or "braking" lugs 18, which are adapted to seat in 100

shallow sockets 19 formed in the grooves 7. Also the same kind of lugs can be formed on the screen, Fig. 13, for preventing accidental displacement of the screen off the casing 1. 5 It is to be understood that both the brush head and the screen will be slid on and off of the casing 1, at the will of the operator, but by employing the shallow sockets 19 and the braking lugs 18, the parts will not rattle nor 10 will they work loose or be accidentally disassembled. As shown by dotted lines "A", Figs. 4 and 10, the casing 1 and the body 28 have a springy or expansible action.

In the top of the handle 2 near the inner 15 end of the casing 1, I form an elongated aperture 20. Extending through this aperture is the rearwardly-extending flat stem 21 of the control device 22. The control device includes said stem 21, presser plate 23 and 20 thumb-plate grip 24. The presser plate 23 is curved transversely to fit upon the rubber tube 6, and has a slight sliding movement thereon as hereinafter explained. The flat stem 21 is integral with the top of the presser 25 plate, and this stem has a straight rear edge 25 and a peculiarly curved front edge 26, for the purpose hereinafter specified. The grip 24 is preferably serrated upon its outer face to better accommodate the thumb or finger 30 of the operator. By pressing inwardly upon the grip or plate-grip, the operator can force the liquid forward into the rubber tubing 6, similar to a pumping action, or if he desires, he can press strongly inward upon the grip 24 causing the pressure plate 23 to collapse the tube 6, closing the same, for preventing liquid passing from the reservoir-handle into tube 6 if it is so desired. When the operator presses upon the grip 24, the tendency is to 40 cause pressure plate 23 to move downwardly and slightly forwardly upon the tube 6. This also causes the curved front edge 26 of stem 21 to be pressed against the inner end of slot 20, but owing to the peculiar curvature of the front edge 26, there will be no binding action, as the resiliency of the rubber tube 6 is such as to force or cause the stem 21 to ride outwardly, when manual pressure is sufficiently removed from grip 24 to permit 45 this action. In other words, the "stroke" of the control device 22 is forward, causing the straight rear edge 25 to ride freely over the rear end of slot 20, whereas the front curved edge 26 will ride under the front end of slot 20, ready to slide back over this end as the pressure of the operator's thumb or finger varies upon the control device.

In Figure 7, the cover 27 is placed upon the body 28 (Fig. 10) of the casing and screws 29 are used to fasten the cover in place. The screen shown in Figures 7 and 8 is also fastened in place by screws 30, Fig. 7. My simple braking lugs and sockets hereinbefore described for the embodiment shown in Figures 1 and 2 lock the brush head and

screen in position, whereas in the embodiment shown in Figure 7, I employ screws for holding the parts assembled. The brush head shown in Figure 10 is of the same general construction as the brush head shown in Figure 4. The control device shown in Figure 7, for this embodiment, is of the same structure as shown in the embodiment depicted in Figures 1 to 5.

The shampoo unit or brush head in Figures 11 and 12 comprises a frame 10, similar to the frame illustrated in Figure 6, with the rubber teeth 31 depending upon the bars of the frame 10. This shampoo unit or head (Figs. 11 and 12) can be easily and quickly substituted for the bristle type head, and is admirable for use in shampooing.

As hereinbefore mentioned, the dotted lines "A", Figs. 4 and 10 indicate that the casing 1 and the body 28 can sufficiently expand to allow the seating of the lugs 18 in the sockets 19, or the unseating of same when it is desired to separate the parts of the brush.

It will therefore be seen that I have produced a fountain type brush, excellent for use in shampooing, and which comprises either a bristle head or a rubber toothed head or unit, assembled with the body casing and handle. Further, I have shown means for efficiently locking the parts together against accidental displacement or disassembling. I have shown an efficient control device for assisting in "pumping" the liquid from the reservoir-handle to the head of the brush or efficiently preventing the liquid from flowing, as the operator desires.

While I have described the preferred embodiments of my invention and illustrated the same in the accompanying drawings, certain minor changes or alterations may appear to one skilled in the art to which this invention relates, during the extensive manufacture of the same, and I, therefore, reserve the right to make such changes or alterations as shall fairly fall within the scope of the appended claims.

What I claim is:

1. In a device of the class described, the combination of an outwardly bulged casing integral with a reservoir handle, a brush head slidably positioned within the inner face of said outwardly bulged casing, a slideable screen between said brush head and said casing, and an apertured flexible tubing within said outwardly bulged casing contiguous to said screen and communicating with said reservoir handle.

2. In a device of the class described, the combination of an outwardly bulged body casing integral with a reservoir handle, said body casing provided with an open inner face and with guiding grooves on its sides, a brush head unit and a screen unit slidably mounted in said grooves, said reservoir handle provided with a tip, and an apertured tube

mounted at one end on said tit and positioned between said outwardly-bulged body and said units.

3. In a device of the class described, the combination of an outwardly-bulged body casing integral at its inner end with a reservoir handle, said body casing open on its inner face, a rigid tit closing the inner end of said reservoir handle contiguous to the open inner face of the body casing, a brush head unit closing the inner face of the body casing and provided with an inwardly-extending protecting tongue extending under said tit, and an apertured rubber tube fitted at one end on said tit above said protecting tongue and extending over said brush head unit.

4. In a device of the class described, the combination of a body and a reservoir handle, a brush head unit on said body, a rubber tube within said body and communicating with said handle, said handle provided with an elongated slot contiguous to said body, a control device provided with a stem extending through said slot and adapted to have a sliding movement within said slot, and said control device provided with a pressure plate resting on said rubber tube.

5. In a device of the class described, the combination of a body and a reservoir handle, a brush head unit in said body, a rubber tube within said body and communicating with said handle, said handle provided with an elongated slot contiguous to said body and over said rubber tube, a control device provided with a rearwardly-extending flat stem, said stem extending through said elongated slot, said stem provided with a straight rear edge and with a curved front edge, a transversely curved pressure plate integral with the inner end of said stem and normally resting on said rubber tube, and a thumb plate or grip integral with the outer end of said stem.

45 6. In a brush of the class described, the combination of a handle and a hollow body, a brush head unit provided with a rearwardly extending tongue detachably mounted on said hollow body, a rubber tubing above said tongue and communicating with said handle, and a manually operated control device engaging said tubing above said tongue and adapted to slightly slide upon the tubing and also to be held in an extended or inoperative position by said tubing.

In testimony whereof I hereunto affix my signature.

CLAUDE C. CROUCH.
